UNITED STATES PATENT OFFICE

JAMES BALTON, OF BALTIMORE, MARYLAND

DESIGN FOR AN ICE CREAM CONE

Application filed February 21, 1933. Serial No. 47,288. Term of patent 14 years.

To all whom it may concern:

Be it known that I, JAMES BALTON, a citizen of the United States, residing at Baltimore, State of Maryland, have invented a new, original, and ornamental Design for Ice Cream Cones, of which the following is a specification, reference being had to the accompanying drawing, forming a part hereof.

Figure 1 is a perspective view of an ice cream cone embodying my design.

Figure 2 is a plan view of the ice cream cone embodying my design.

Figure 3 is a side elevation of the same looking in the direction of the arrow in Figure 1.

What I claim is:

The ornamental design for an ice cream cone substantially as shown.

JAMES BALTON.
